UNITED STATES PATENT OFFICE.

NEWTON L. SNORF, OF CHICAGO, ILLINOIS, ASSIGNOR TO EDMUNDS & JONES CORPORATION, A CORPORATION OF NEW YORK.

FOCUSING SOCKET.

Application filed June 3, 1922. Serial No. 565,600.

To all whom it may concern:

Be it known that I, NEWTON L. SNORF, citizen of the United States, residing at Chicago, in the county of Cook and State 5 of Illinois, have invented certain new and useful Improvements in a Focusing Socket; and I do hereby declare the following to be a full, clear, and exact description of the invention, such as will enable others skilled 10 in the art to which it appertains to make and use the same.

My invention relates to sockets for electric lamps, and in one of its general objects aims to provide an unusually simple and 15 inexpensive socket construction which will be particularly suitable for use under conditions in which it is necessary or desirable to adjust the position of the socket longitudinally thereof.

20 In another aspect, my invention relates to the class of lamp sockets employed with lamps of the so called Ediswan type (or lamps which have one end of the filament grounded to the metal base of the lamp). 25 In this aspect I aim to provide an unusually cheap and effective arrangement of the circuit connection to the socket shell, as well as an unusually simple, easily assembled and adequately insulated arrangement 30 of the other parts of the socket.

More particularly, my invention aims to 35 provide simple means for connecting the circuit wire to the relatively thin shell of a lamp socket without depending on a thread tapped into such a thin shell. It also aims to provide simple means for attaching the socket and for insulating the shell from this support, and desirably aims to employ the insulation used for this purpose also as means for resisting the thrust 40 of a spring which normally holds the axial terminal of the socket in contact with the corresponding terminal of the lamp. Furthermore, my invention aims to provide a 45 socket of this general class which can easily be wired and in which both of the needed wire connections can readily be made direct to the socket portions which contact with the lamp terminals. It also aims to 50 provide simple means for retaining the mov-

able body member of the socket within the socket shell while permitting this member to be withdrawn from the shell for making the circuit connection to the same. Still further and also more detailed objects will 55 appear from the following specification and from the accompanying drawings, in which Fig. 1 is an elevation of a focusing socket embodying my invention, showing the same as holding a corresponding lamp. 60

Fig. 2 is a plan view of the same embodiment with the lamp detached from the same.

Fig. 3 is an enlarged central and vertical section taken through the socket of Figs. 1 65 and 2 along the line 3—3 of Fig. 2.

Fig. 4 is a horizontal section taken through the socket along the line 4—4 of Fig. 3, with the focus-adjusting portions below the socket shell omitted. 70

Fig. 5 is a central and vertical section taken through the body member of the socket at right angles to that of Fig. 3.

In the drawings, I am showing a socket 75 embodying my invention and mounted on a particular type of support such as is now commonly employed in railway signal lamps, though I do not wish to be limited to its use in that particular connection. In this illustrated embodiment, the socket includes a shell 1 having a substantially cylindrical main portion equipped at its forward end with the usual bayonet slots 2 for receiving laterally projecting pins 3 on the base 4 of a miniature Ediswan lamp 5. The 80 socket shell 1 desirably is cylindrical for its main portion and desirably has near its forward end a pair of spring fingers 6 which are bent slightly inward of the shell so as to afford a friction contact with the 85 metal shell 4 of the lamp base, which lamp base shell is grounded to one end of the lamp filament.

To make the corresponding circuit connection to the socket shell 1, I desirably 90 form an ear 7 from this shell, which ear extends at an acute angle with the shell portion rearwardly thereof and is perforated for receiving a screw 8 threaded into a nut 9, the head of the screw being dis- 100

posed on the outer side of the finger 7 so that the screw can be used for clamping the tip of a circuit wire 10 between the said finger and nut. By employing a nut somewhat wider than the finger 7 and by disposing this finger at an angle to the axis of the socket shell, I cause the nut to overlap the longitudinal edges of the aperture formed in the shell by punching out this finger, so that the resulting engagement of the nut with the walls of the perforation will prevent the nut from turning and hence will insure a firm clamping of the wire.

15 To support the socket shell, I mount within the rear end thereof an annular insulator 11, for which purpose I desirably enlarge the diameter of the rear end of the shell for a distance slightly greater than the thickness of the insulator 11. I also indent into the rear face of this insulator a plurality of fingers 12 spaced circumferentially of the shell and formed from this shell, so that the indenting of these fingers will prevent the insulator from rotating within the shell and will also hold the insulator against the shoulder at the juncture of the two differently diametered shell portions to prevent the insulator from moving longitudinally of the shell. Then I slip through the bore of the insulator 11 an inwardly threaded bushing 13 presenting an enlarged head on the forward face of the insulator, this bushing being sufficiently enlarged or swedged out the rear of the insulator to clamp it tightly to the latter. Thus attached, the threaded bushing 13 will form a convenient means for securing the socket shell to any threaded supporting portion, such as the threaded tube 14 of Figs. 1 and 3.

For the central terminal of the socket I provide a screw 15 extending through an axial bore in an insulating body 16 which is freely slidable within the socket shell 1 and which has its axial bore enlarged for some distance from its rear end so as to receive the threaded base of a screw-eye 17'. When this screw-eye is loose, the tip of the 50 companion circuit wire 17 can readily be inserted through the eye thereof, after which the screw 15 is tightened so as to draw the eye into the enlarged rear bore 18 of the insulating body and clamp the wire against the bight of the screw eye. When thus fastened, it will be evident from Fig. 3 that the wire is directly secured to the screw 15 which engages the axial lamp terminal and forms the axial terminal of 60 the socket.

To press the last named two terminals into firm engagement, I interpose a spring 19 between the insulating body and the perforated rear head of the socket, in doing which I desirably reduce the diameter

of the insulating body for a considerable distance from its rear end (as shown in Fig. 3) to permit the use of a long spring. I also desirably provide an insulating washer 20 adjacent to and forward of the bushing 13 so as to receive the thrust of the spring 19, and so as to prevent this spring from grounding the socket shell to the said bushing and to the support to which the bushing is connected.

With the parts thus arranged, it will be obvious that when a lamp is inserted in the socket and interlocked with the bayonet slots of the socket in the usual manner, the movable body member of the socket (consisting of the insulator 16, the screw 15 and the screw eye 17') will be moved rearwardly of the socket shell against the pressure of the spring 19. To prevent the spring from ejecting this movable body member when the lamp is detached, I desirably clamp a stop ring 21 on the insulation of the axial circuit wire 17 adjacent to the rear end of the supporting tube 14, so that this stop ring will limit the forward movement of the body member of the socket.

For focusing purposes, the tube 14 desirably extends through a relatively large aperture 22 in a plate 23 supported by risers 24, the tube being clamped to this plate by means of a pair of lock-nuts 25 and 26 which bear respectively against washers 27 and 28 disposed forwardly and rearwardly of the said plate 23. Thus arranged, the size of the aperture 22 will permit a shifting of the lamp socket in any direction transversely of its axis when either of the lock-nuts is loosened, while a shifting in position of the two lock-nuts longitudinally of the tube 14 will correspondingly shift the entire 105 socket with respect to the supporting plate 23.

However, while I have illustrated and described a socket embodying my invention as mounted on a particular and highly desirable type of support, and have disclosed the same in an embodiment including various desirable features, I do not wish to be limited to these or other details of the construction and arrangement here disclosed, it being obvious that the same might be modified in many ways without departing either from the spirit of my invention or from the appended claims.

I claim as my invention:

1. In a lamp socket, an exteriorly threaded tube, means to support the tube, a shell, a fixed perforated insulator housed in one end of the shell, a bushing fixed to the insulator and having interior threads engaged over and with the threads of the tube, an insulating washer engaged over the inner end of the bushing, a contact carrier in the shell, spring means seated on the washer for tensioning the carrier, a

wire extending through the tube and washer and connected to the carrier, and stop means on the wire engaging the opposite end of the tube to restrict movement of the carrier under the action of the spring.

2. In a lamp socket, a tubular member, means to support the member, a shell carried by one end of the member, a slidable spring pressed contact carrier in the shell, 10 a conductor connected to the carrier and

extending through the tubular member to be housed thereby and extending beyond the opposite end of the tubular member, and stop means on the conductor to engage said opposite end of the tubular member thereby to restrict sliding movement of the carrier outwardly of the shell.

Signed at Chicago, Illinois, May 31st, 1922.

NEWTON L. SNORF.
